UNITED STATES PATENT OFFICE.

CHRISTIAN ZIMMER, OF RICHMOND, VIRGINIA.

REFRIGERATOR.

SPECIFICATION forming part of Letters Patent No. 267,963, dated November 21, 1882.

Application filed April 27, 1882. (No model.)

To all whom it may concern:

Be it known that I, CHRISTIAN ZIMMER, a citizen of the United States, residing at Richmond, in the county of Henrico and State of Virginia, have invented certain new and useful Improvements in Refrigerators; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention consists in certain improvements in the construction of refrigerators, more especially the ice-receptacle, as fully described hereinafter and pointed out in the claims, and as shown in the accompanying drawings, in which—

Figures 1 and 2, Sheet 1, show respectively a transverse and a longitudinal vertical section of an ordinary family refrigerator embodying my improvements. Figs. 1^a and 2^a, Sheet 2, are like views, illustrating the invention as applied to the larger class of refrigerators. Fig. 3 is a vertical longitudinal section, illustrating the application of the invention to preserving-chambers or refrigerating-rooms. Fig. 4, Sheet 3, is a like view, showing the application of the invention to portable beer-coolers. Figs. 5 and 6, Sheet 3, show by a vertical transverse section and a like horizontal section the application of the invention to the cooling of malt-liquors and forcing the same from the cooling-chamber to the counter or bar; and Fig. 9, Sheet 1, shows a slight modification of construction thereof. Fig. 7, Sheet 3, is a perspective view of the ice-receptacle; and Fig. 8, Sheet 2, is a detail view of my improved ventilator-register.

Like letters of reference are employed to indicate like parts wherever such may occur in the above-described figures of drawings.

In the above drawings, W indicates the inclosing case or box or walls, which are usually composed of double walls, with a filling between the two of some suitable non-conductor of heat.

In family refrigerators I preferably line the boxes, as usual, with zinc; but in refrigerating-rooms, such as used for the preservation

of large quantities of meat or other perishable substances, and in which comparatively large quantities of ice are usually stored, I find that it is not necessary to line the interior walls at all, for the reason that with the perfect ventilation, as hereinafter described, condensation resulting from the rapid cooling of warm bodies will take place only upon the under side of the ice-receptacle itself, and this moisture is at once conducted from the cooling-chamber.

R is the ice-receptacle, preferably made entirely of zinc, and is composed of a box or receptacle, r, that will be of such a shape as to fit the inclosing walls or box either entirely or partially, according to the capacity of the refrigerating-chamber. As the shape of the inclosing-walls will in large stationary refrigerators depend upon that of the space where it is erected, or in family refrigerators upon the shape given to the inclosing-case, said ice-receptacle will therefore vary in shape accordingly. The depth of the receptacle r will also vary with the capacity of the cooling-chamber, 75 as will be readily understood, and said receptacle has a concave imperforate bottom, r', slightly inclined from one end of the receptacle to the other, as shown. The ice-receptacle has one or more depending flues, R', extending 80 from the ice-receptacle downward. Said flue or flues may be of such a length as to reach to the bottom w of the refrigerating-chamber C, as shown in Figs. 1^a, 2^a, 5, and 6, or said flues may extend a certain distance only into the 85 said refrigerating-chamber, as shown in Figs. 1, 2, 3, 4, and 9. If the receptacle has two such flues R', which will generally be found sufficient even for very large refrigerating-chambers, one of the flues may be extended to 90 the bottom of said chamber and the other to about midway (more or less) of the said chamber, as shown in Fig. 3.

At or near the bottom or lower end of the flue or flues is a ventilating-aperture, V, provided with a register-slide, S, or other suitable device for regulating the admission of air. This ventilating-aperture communicates with a pipe, P, that serves to carry fresh air to the lower part of the refrigerating-chamber C. In 100 family refrigerators the said pipe P may be conducted out of the refrigerator through one

of the walls thereof and provided with a suitable register, as shown in Figs. 2 and 2^a, or it may be conducted through the lids L L' of the refrigerator and provided with a register, p, as shown in Fig. 1^a. The air flue or flues R' of the ice-receptacle are further provided with a series of cold-air ports, a and a', the former located near the upper end of said air flue or flues R' and the latter near their lower end. The admission of the cold air from the ice-receptacle through said ports a and a' is regulated by means of suitable register-slides, s and s', respectively. These register-slides may be operated from within the refrigerating-chamber, or they may be connected to a rod that passes through the inclosing-walls, said rod being there provided with suitable indices to show the extent of closure of said ports by the slide, as shown, Fig. 1^a, where the full opening of the ports a or a' is indicated when the stop b' on the operating-rod lies against the inner wall of the box, and the full closing is indicated when the stop b lies in contact with the outer wall of said box; and the space of the rod between the stops may have notches b², that will indicate the extent of the partial closure of said ports.

The ice-receptacle in small refrigerators, when provided with two downwardly-projecting cold-air flues R', needs no further support, as these flues then serve as legs upon which the receptacle is supported, and when but one flue is employed then the end of the ice-receptacle opposite said flue will rest upon any suitable support within the inclosing-case. In large refrigerators, when the weight of the ice would be too great for the strength afforded by the cold-air flues R', or in such cases where said flues do not extend to the bottom of the refrigerating-chamber, I form a cradle, I, by means of iron straps i, in which the ice-receptacle R is suspended, said straps being secured to the inclosing-walls.

As above stated, it is not essential to the good operation of the ice-receptacle that it should occupy the entire upper space of the inclosing-box. As shown in Fig. 1, it extends only partially over the upper part of the box, and between one of its walls and the inclosing-case is formed an additional refrigerating-space, C², said wall being provided with air-ports a², provided with register-slides s², to establish an interior circulation of air, as will be described hereinafter.

Below the concave bottom of the ice-receptacle R is suspended a concave drip-pan, D, for collecting the vapors that condense upon the bottom of the ice-receptacle, this being the only place, as practically demonstrated by experience, where such condensation takes place, and for this reason I do not line large refrigerators with zinc, as usual.

The bottom of the ice-receptacle could be made flat, if desired. This construction, however, has two serious disadvantages, in that it requires a drip-pan of the same width as the

ice-receptacle, and, secondly, in that both the water resulting from the condensation of vapors as well as the water resulting from the melting of the ice would run into the air-flue 70 along its entire width, which is not desirable.

The bottom r' of the ice-receptacle as well as the drip-pan are respectively provided with a discharge-spout, r² d, that conduct the water into one of the cold-air passages or flues R', 75 from whence it is discharged in the usual manner, by a pipe, P', arranged to prevent the access of air to the cold-air flue, either by a water luting, as shown in Figs. 2^a and 3, or by an adjustable siphon-discharge, as shown in 80 dotted lines in the latter figure, or by providing the discharge-pipe with a stop-cock. In the latter case, where but one cold-air flue R' is used, the air-ports V and a' must be located sufficiently far from the bottom of the flue to 85 allow a certain volume of water to collect therein without flowing into the refrigerating-chamber and be drawn off from time to time.

T is a pipe that places the ice-receptacle in communication with the preserving-chamber, 90 and T' is a like pipe that places said receptacle in communication with the outer atmosphere. Each of said pipes has a register, t and t', respectively.

In all cases I prefer to construct the inclosing-case and ice-receptacle in such manner as to admit of the latter being lifted out of the inclosing box or walls, which is especially desirable in family refrigerators for the purpose of cleansing. In this case the operating-rods 100 for the cold-air registers are screwed into sleeves formed on said registers, and the inner stop, b', is screwed upon said rod, and the waste-water discharge and air pipe must also be arranged so as to be readily disconnected 105 from the ice-receptacle or removed from the inclosing-case with it, as shown in Fig. 1^a, where the pipe P is extended through the lids L L'.

To prevent the ice from falling into the cold-air flue or flues, I form a grating, F, across the opening.

The refrigerating-chamber has ports e', provided with registers E, immediately below the bottom of the ice-receptacle, that communicate 115 with pipes e, leading to the outside of the refrigerator, as shown in Figs. 2^a, 3, and 6.

In family refrigerators I employ preferably two lids—an outer lid, L, covering the entire refrigerator, (which is provided with a second lid, L², Fig. 2^a, when such refrigerators are of a size to make the outer lid too heavy,) an inner lid, L', covering the ice-receptacle, which is also provided with a second lid, L³, and I leave sufficient space between the two lids to 125 form a chamber, C', into which the foul air is discharged. The lids L' L³ are made to fit tight one upon the other and upon the ice-receptacle, and the lid L is not fitted tightly so that the foul air can escape when the lid is not 130 opened for some time. The lids L² L³ serve to introduce the ice into the receptacle and the

lids L and L' to withdraw the receptacle from the box. In Figs. 5 and 6 I have shown the receptacle applied to a retail liquor-store.

The counter M, having the faucets from which the malt-liquors are drawn is in communication with the refrigerator, and preferably in such manner as to permit the conducting-pipes m for the liquor to be carried down the cold-air flue R', and not through the ice-receptacle, and through that cold-air flue (where two are employed) into which the waste water is not discharged, as shown in Fig. 6.

The refrigerator being, as shown, located in the cellar or basement below the store, the foul air may be discharged directly into a chimney, N, and the fresh air taken through pipe P from any convenient point inside or outside the store or building, the refrigerating-chamber being fitted not only for the storing and cooling of one or more casks, but also for storing and cooling perishable articles, and has shelves Q, as shown in Fig. 6. The counter M is here made to serve as an additional refrigerator, and may be provided with shelves 25 or trays for the cooling of liquids in bottles, and also for maintaining the malt-liquors ascending through pipes m at the desired temperature.

In Fig. 9 I have shown a slight modification of the above-described construction. The pipes m, that convey the malt or other liquor to the faucets, are inclosed within the cold-air flue R' of the ice-receptacle of the upper refrigerator, and are connected to pipes P³, arranged in the floor or in the wall of the lower refrigerator, and surrounded by any suitable non-conducting material, p³, said pipes being also contained in a pipe, P², that passes through the ice-receptacle of the lower refrigerator.

To the lower end of pipes p³ one extremity of one or more flexible pipes, m', is connected; the other end being connected with a cask or casks. The water resulting from the melting of the ice or from condensation of vapors is discharged from the upper refrigerator into the flue R' of the lower refrigerator, that receives the water from its own ice-receptacle and drip-pan through pipe P, as shown.

The operation of the refrigerator is as follows: When first charged with ice to rapidly cool the chamber C, or when said chamber has been supplied with a large quantity of perishable articles to be cooled, the registers s and s', as well as those t t' upon pipes T and T', are thrown open, as well as the slide S, the slide E remaining closed. A circulation of air is at once established between the outer atmosphere, the ice-receptacle, and the chamber C, the air being drawn through pipes T' P. The air coming in through pipe T' is cooled on passing over the ice and enters the refrigerating-chamber through flue or flues R' and the ports a and a', while the air coming in through pipe P is cooled on its passage through said flues R' and enters the refrigerating-chamber. It will be seen that cold air is thus supplied to

the refrigerating-chamber at different elevations, and the warm air displaced thereby passes through pipe T into the ice-receptacle and returns to the chamber C in a cooled condition. It will thus be seen that an interior circulation of air is established that rapidly lowers the temperature of the refrigerator. When the temperature within the chamber C has been lowered sufficiently the register t' upon pipe T' is closed. This register, admitting air directly to the ice, causes it to melt rapidly; hence is closed as soon as the chamber C is sufficiently cooled. The register E is then opened and the foul air conducted away from the chamber C through pipe e, fresh air being admitted through pipe P, as before, and as the pipe e does not communicate with the ice-receptacle or its flues, but is located in the refrigerator-walls, the melting of the ice practically ceases, and the temperature is gradually lowered within the chamber and flues, thus correspondingly lowering the incoming air as it passes down the pipe P, which itself passes through the ice-receptacle and down one of the flues R'. When the substances stored are thoroughly cooled the slides S, s, s', and E are partially closed, or may for a time be entirely closed.

Any suitable construction of register may be employed either upon the pipes inside or outside of the refrigerator or upon the cold-air ports a and a'. The ends of the pipes leading to the outside of the refrigerator should, however, be provided with registers that will exclude insects therefrom. For this purpose I preferably employ the register H, (shown in Fig. 8,) which is composed of a head, h, to which is attached a cylinder, h', of woven-wire fabric. Said cylinder may be fitted upon the outside of the pipe, or it may be arranged to slide into the said pipe. In either case the head h is or may be provided with a handle, h², and the outer or inner periphery of the pipes with a spiral groove, p², into which fits a lug or lugs, h³, connected with the re-enforcing band h⁴ of the woven-wire cylinder, so that on revolving said cylinder it may be raised to any desired extent and held in that position. The cylinder may have two or more such re-enforcing bands, which may be connected together and to the head by means of stay-rods, to give said cylinder greater rigidity.

Having described my invention, what I claim is—

1. In a refrigerator, the combination, with an inclosing-case, of an ice-receptacle having one or more cold-air flues formed integral therewith, depending from the floor thereof, and extending across its entire width, means, substantially such as described, to prevent the ice from entering said flues, means for conducting the cold air from the flues into the refrigerating-chamber at or near the lowest point, means for admitting air from the outside of the refrigerator through said flues into the cooling-chamber without bringing such air in direct

- contact with the cold air in such flues, and means for conducting the warm or foul air away from the chamber through the walls of the refrigerator, all arranged for co-operation substantially as described and shown. 5
2. In a refrigerator, an ice-receptacle provided with one or more diving-flues, closed at bottom and opening into the ice-receptacle at top, said flue or flues being provided with registers to conduct the cold air from the ice-receptacle to the cooling-chamber, and serving as a receptacle for the waste water, as described. 10
3. A sheet-metal ice-receptacle for refrigerators, consisting of the vessel R and one or more diving-flues, R', closed at bottom and serving as supports for said ice-receptacle, substantially as and for the purpose specified. 15
4. An ice-receptacle for refrigerators, having a concave bottom and one or more diving-flues, serving as cold-air passages and as a receptacle for the waste water resulting from the melting of the ice, said flues being provided with cold-air ports and a port for the discharge of the waste water, as described. 20
5. An ice-receptacle for refrigerators, consisting of the vessel R and one or more diving-flues, R', adapted to serve as supports for said receptacle and as conduits for the cold air, in combination with an inclosing-case, in which said receptacle is removably fitted, and by which said case is divided into an ice-receptacle and cooling-chamber, as described. 25
6. In a refrigerator, the combination of an inclosing-case, an ice-receptacle provided with one or more diving-flues, closed at bottom and opening into said receptacle at top, said flue or flues being provided with registers to conduct the cold air from the receptacle into the cooling-chamber, and an air-pipe contained in said flue or flues opening into the atmosphere at one end and the cooling-chamber at the other, 30
- whereby the atmospheric air conducted to the cooling-chamber is first cooled by and without bringing it in direct contact with the cold air 45 passing through the flues, as described.
7. In a refrigerator, the combination, with the inclosing-case provided with a cradle, of an ice-receptacle removably suspended from said cradle, as and for the purpose specified. 50
8. In a refrigerator, the combination, with the inclosing-case provided with a cradle, of an ice-receptacle and a drip-pan for collecting the water condensed upon the outside of said receptacle, both suspended from said cradle, 55 as and for the purpose specified.
9. In a refrigerator, the combination, with the inclosing-case, of the ice-receptacle R, provided with a diving flue or flues, R', having adjustable ports a, a', and V, of the air pipe or pipes P contained by said flues, and opening into the atmosphere at one end and into the cooling-chamber through said adjustable port V at the other, all arranged for co-operation as described. 60
10. The combination, with the ventilating-pipes, of the register H, adjustably fitted upon or within said pipes, as described, and composed of a cylinder of woven-wire fabric and a solid head, substantially as and for the purpose specified. 65
11. The combination, with the ventilating-pipes having a spiral groove, p², of the register H composed of a cylinder of woven-wire fabric, provided with a solid head and a lug 70 adapted to fit into said groove, substantially as for the purpose specified. 75

In testimony whereof I affix my signature in presence of two witnesses.

CHRISTIAN ZIMMER.
